SHEAVE AND PRESSURE RIDER

Joseph C. Patterson, Jr., Alexandria, Va.

Application August 21, 1941, Serial No. 407,811

5 Claims. (Cl. 254—176)

This invention relates to a combined sheave and pressure roller for handling a cable and more particularly it has reference to such combination wherein the sheave is driven and is of a novel structure adapted to grip the cable throughout a substantial proportion of the surface thereof.

Sheaves of the present type, although of wide adaptability to any number of hoisting problems, are of particular utility in conjunction with the paying out device on the outboard end of the boom of a crane employed for handling ship-borne aircraft and the like. In hoisting aircraft abeam ships, it is customary to use a hoist having a paying out device acting upon and serving to drive the hoist cable so that the use of a weight in the hoisting whip may be avoided, the latter being a dangerous expedient because of the fact that the cable suspended weight may swing to and fro and in so doing damage the plane or injure the occupant thereof during the initial hook-on period. A paying out device of the type in question is disclosed in my Patent No. 2,042,481, issued June 2, 1936.

In the employment of sheaves for paying out cable in the manner outlined above, it is, of course, necessary to provide some suitable means for driving the sheave and for imparting the movement thereof to the cable without slippage. It is the usual practice to insure sufficient driving friction between cable and sheave by applying pressure through a roller disposed to make tangential contact with the cable and being acted on by a force tending to urge it radially toward the axis of the sheave. The required pressures in the case of sheaves of known construction are rather high and consequently result in a severe squeezing action on the cable tending to force out the lubricating and corrosion inhibiting composition with which the hemp core thereof is customarily saturated. Both the loss of lubricant and the intense pressure contribute to excessive wear on both cable and sheave. Then too, the high pressure used has also been a source of difficulty in automatic tension hoists, the power required for merely pulling the cable through the sheaves being of a high order. In an attempt to avoid, at least in part, these difficulties, the pressure rider has been heretofore mounted in a complicated manner to release the cable at all times when the device is not actually paying out cable.

A further difficulty which has arisen in connection with paying out sheaves of the type heretofore known is lack of adaptability for use with cables of differing diameters and consequently inability to compensate for wear of either the

sheave groove or the cable. The result of the foregoing is, of course, frequent and costly replacements.

It is therefore an object of this invention to provide a paying out device in which adequate driving friction between cable and sheave is maintained at an optimum value while damage to and wear of both cable and sheave is minimized.

The present invention contemplates a driving sheave and cooperating pressure roller so constructed and arranged that satisfactory paying out is achieved with the use of moderate pressures. The invention further contemplates the provision of a sheave of such construction that the essential element in achieving the said result is formed of a substance which not only is peculiarly adapted for permitting reduced operation pressures, but also provides a cable contacting surface of high wear-resistant quality.

Concomitant to the advantages set out above is a wide adaptability to operation with cables of a size varying with respect to the riding surface of the sheave.

Other objects and advantages of the invention will be apparent from a consideration of the following detailed description of several preferred forms of the invention in conjunction with the annexed drawings wherein:

Figure 1 is a view showing the relationship of drive sheave, cable and pressure rider according to the present invention;

Figure 2 is a partial section through the axis of the sheave according to one form of the invention;

Figure 3 is a section similar to that of Figure 2 and illustrates the operation of the sheave upon the application of pressure to the cable;

Figure 4 is a fragmentary view in section, similar to that of Figure 2, illustrating a modified form of the invention;

Figure 5 illustrates a modification employing a plurality of pressure riders;

Figure 6 represents a modification of the embodiment shown in Figure 2;

Figure 7 is a plan view partially in section of the embodiment shown in Figure 6; and

Figure 8 is a partial plan view showing a modification wherein the cable-carrying surface of the sheave is provided with a tread.

In general, the invention contemplates the combination of a driver sheave and pressure rider wherein the sheave is constructed with a resilient body or spool mounted in position by rigid members but adapted to be deformed in a novel manner in its peripheral portion. The periphery

of the resilient body is formed with a circumferential groove for carrying the cable. The provision for deformation of the resilient spool is such that the sides of the groove will be forced inwardly to bear against a substantial proportion of the surface of the cable upon pressure being applied to the cable through the medium of the pressure roller.

Referring specifically to Figures 1 and 2, a cable 10 is carried between a sheave 11 and a pressure roller 12, provided with a suitable means for application of pressure, such as the hydraulic cylinder 21, illustrated in Figure 1. The sheave 11 comprises rigid flanges 13 and a resilient body portion 14 of a synthetic rubber material maintained in place between the flanges by a plurality of clamping bolts 15. The flanges are mounted on a shaft 16 by conventional means and the shaft 16 is provided with suitable driving means, not shown. In the embodiment of Figures 2, 3 and 7 the inner faces of the flanges 13 are provided with recesses 17 and the bolt 15 passes through a bore in the body 14 of considerably greater diameter than the bolt.

By reference to Figure 3 it is seen also that the application of pressure to the cable by means of pressure roller 12 causes the resilient body 14 to be deformed, bulging outwardly into the recesses 17 and also causing the walls of the groove 18 to close in against the cable 10 thus providing a much greater area of contact between the cable and that portion of the sheave contacting therewith.

In the embodiment of the invention shown in Figure 4, flanges 13 are not provided with recesses 17, but rather, the resilient body portion 14 is arranged with cut-out portions 17a. It is evident that recesses 17 and recesses 17a have the same function. The importance of these recesses is their location with respect to the material defining groove 18 which is such as to cause the resilient material to bend around the cable as shown in Figure 3 when pressure is applied from the rider. Inasmuch as the material from which body portion 14 is composed is deformable rather than compressible, it is evident that recesses 17 and 17a also function to prevent the synthetic rubber material from being ground out because of bearing against a hard surface.

By means of the device discussed above, it is found that wear on the cable is greatly reduced by the coaction of two factors. Because of the adjustable gripping action of driving contact between sheave and cable, it is possible to use drastically reduced pressures. Further, the wear due to friction between the surface of a metal and a resilient substance is much less than the wear due to friction at a metal-to-metal contact. Although I may use rubber or any other resilient substance, I prefer to use the so-called "synthetic substances" because of their greater resistance to deterioration in the presence of oils such as are used for lubrication and corrosion inhibition of the cable. Such synthetic compositions as "neoprene," "Thiokol," "Formica" and the like are found to be eminently satisfactory. I have also found that the use of the present device results in longer life of the cable because the tendency to squeeze out the oils used for lubrication and corrosion inhibition is greatly reduced.

By the use of a resilient body 14 disposed between rigid flanges 13 which may be drawn together by bolts 15 it is evident that the initial diameter of groove 18 can be adjusted to receive

cables of different cross sectional areas. Furthermore the size of the groove may be altered to compensate for wear by merely drawing flanges 13 together. This adjustment therefore renders installation less difficult and replacement less frequent.

Still greater advantages under certain drive conditions are obtained by using a system such as that shown in Figure 6 wherein the cable is caused to lie in the groove 18 for a large portion of the periphery of the drive sheave 11 by the use of a plurality of pressure riders 12. It will be apparent that the increased contact area will prevent excessive wear of the resilient material by reducing the intensity of pressure as contrasted with the prior art expedient of maintaining positive drive by the use of extremely high pressure.

In Figure 7 there is shown a modification of the embodiment illustrated in Figure 2. A plurality of clamping levers 19 are provided along the two edges of the resilient body in the peripheral portion of the sheave. Each of the clamping levers 19 is of a form similar to a bell crank pivoted for rotation in a plane parallel to the axis of the sheave on the inner face of flange 13. One leg of each lever 19 lies between flange 13 and resilient body 14 extending radially outward from the point of pivotal connection. The other leg is embedded in the resilient body 14 extending into that body and toward the axis of the sheave. Upon application of pressure to the cable 10 the cable tends to displace a portion of the resilient body 14 inwardly toward the axis of the sheave thereby acting upon the inner legs of the levers 19. By reason of the pivotal connection of the levers to the flanges 13, the outer legs of the levers are caused to exert pressure against the resilient body toward the cable thus accentuating the effect illustrated in Figure 3.

I have found that efficiency of the sheave may be enhanced by providing a tread in the cable carrying groove of the resilient body 14. Figure 8 illustrates a resilient body 14 having radial slots 20 extending from the surface of the groove 18 a substantial distance into the body 14. Preferably the depth of the slots 20 is substantially equal to the depth to which the groove 18 will be worn before replacement is advisable.

It will be apparent to those skilled in the art that various modifications and adaptations of my invention may be made without departing from the spirit thereof. For example, it is often advisable to incorporate friction enhancing materials such as metal wire, fibre, hemp, carbon, and other substances having suitable properties in the resilient body 14. It is to be understood that the invention is not limited to the specific forms illustrated and discussed, but is limited only by the scope of the appended claims.

What I claim is:

1. In the combination of a sheave having a peripheral groove to receive a cable, rope or belt, a rider cooperating with said groove and pressure means to apply pressure to said rider; a sheave comprising rigid circular flanges forming sides of the sheave and each having its inner face recessed throughout a portion thereof intermediate the axis and the periphery of the sheave and a resilient body portion having a peripheral groove lying between said flanges and normally occupying the space between said flanges

with the exception of the space in said recessed portions.

2. A device as defined in claim 1 having a plurality of clamping levers pivotally attached to the inner faces of said flanges outwardly of said recessed portions, one leg of each of said levers extending radially outward between said resilient body and said flange and the other leg thereof extending at an acute angle to the face of said flange into said body and toward the axis of the sheave.

3. In the combination of a sheave having a peripheral groove to receive a cable or the like, a rider co-operating with said groove and means to apply pressure to said rider, a sheave comprising rigid flanges forming the sides thereof, a resilient body portion having a peripheral groove, said body portion lying between said flanges and being normally in contact therewith except in annular zones, each of which is defined,

at least in part, by an inner face of a flange, the radial depth of the body portion being at least twice the diameter of the groove, and means passing through said zones for drawing 5 said flanges toward one another to reduce the diameter of said groove, whereby to render the sheave adaptable to use with cables of different diameters and to allow compensation for wear of the groove.

10 4. A device as defined in claim 1 wherein said resilient body portion is provided with a plurality of radial slots extending inwardly from the bottom of the peripheral groove to afford improved cable gripping qualities.

15 5. A device as defined in claim 3 wherein said resilient body portion is provided with a plurality of radial slots extending inwardly from the bottom of the peripheral groove to afford improved cable gripping qualities.
